SHOE CLEANING-POLISHING DEVICE

Andrew W. Brainerd, Kent H. Brainerd, and Stuart W. Brainerd, all of 630 Walden Road, Winnetka, Ill. 60093

Filed Mar. 5, 1971, Ser. No. 121,619

Term of patent 14 years

Int. Cl. D4—99

U.S. Cl. D86—11

Fig. 101

Fig. 102

Fig. 103

Fig. 104

FIG. 101 is a lateral view of the shoe cleaning-polishing device pictured sectionally in FIG. 103.

FIG. 102 shows a front view of the shoe cleaning-polishing device shown in FIG. 101 and which is shown sectionally in FIG. 103.

FIG. 103 shows a sectional view of the device pictured in FIGS. 101 and 102, said sectional view being taken at a level approximately that of the double arrows shown in FIG. 101.

FIG. 104 depicts sectionally an additional species of the invention covered in this application, said section taken at the level of the double arrows of FIG. 101.

We claim:

The ornamental design for a shoe cleaning-polishing device, substantially as shown and described in this application.
